UNITED STATES PATENT OFFICE.

JOHAN KAREL FREDERIK BLOKHUIS, OF MIDDELHARNIS, NETHERLANDS.

BURNER FOR INVERTED INCANDESCENT GASLIGHTS.

1,316,014.

Specification of Letters Patent. Patented Sept. 16, 1919.

Application filed November 20, 1916. Serial No. 132,345.

To all whom it may concern:

Be it known that I, JOHAN KAREL FREDERIK BLOKHUIS, managing director of gas works, a subject of the Queen of the Netherlands, 5 residing at Zandpad B, Middelharnis, Netherlands, have invented certain new and useful Improvements in Burners for Inverted Incandescent Gaslights, of which the following is a specification.

10 The invention relates to improvements in burners for inverted incandescent gaslight and has for its object to prevent the rupture and loss of the baked nozzle, commonly called tips, from which the ring which bears 15 the mantle is suspended. It is known that the mantles of inverted burners are fastened to a ring or the like which is suspended from a nozzle of baked magnesia or pipe-clay. This nozzle is nearly always fastened 20 to the somewhat widened end of the metal burner tube in such manner that a thread formed on the outside of the baked nozzle fits into a corresponding thread on the inside of the widened end of the metal burner tube. 25 A very disagreeable and dangerous drawback of the inverted burner is that sometimes the burner tip, when in a state of incandescence, is apt to snap off suddenly at the tapped part and to fall down together 30 with the mantle. No means being usually present to intercept them, fires have often been caused in this manner, especially in shop windows.

It has been generally understood that the 35 breaking of the tip was due to the tight screwing thereof into the burner tube combined with an unequal expansion of the material of the tip and that of the burner tube. If this explanation were true the tip would 40 as a rule break off as soon as the parts grow hot on lighting the lamp for the first time. This however is not the case; the falling down of the burner tip occurs unexpectedly 45 after the burner has been used for some months.

The inventor found that the part of the broken tip, which is left behind is always embedded in a hard layer, formed by chemical action of the flame-gases on the metal of 50 the burner tube. This layer steadily increases in thickness, after a time completely fills up the space between the burner tube and the tip and finally squeezes off the tip.

That this is the true explanation of the rupture of the tip was shown very clearly in one 55 particular case in which the tip had not been ruptured over its whole circumference but had remained intact on one side. When afterward it broke off also at this place and fell down it was seen that the old fissure was 60 totally filled up with the above mentioned deposit which evidently had been under considerable pressure.

The damage can therefore be avoided by preventing the reaction of the flame-gases 65 on the metal of the burner tube and it was proved that the breaking off of the tip was indeed avoided by such means as make this reaction impossible.

The chief feature of this invention, therefore, resides in the fact that means are provided which resist the reaction of the gases of the flame on the metal of the burner tube thus preventing the formation of compounds which accumulate in the space between the 75 tube and the tip and whose growth may cause in the end the breaking off of the tip. The tip itself cannot be done away with because if formed of metal alone it would too 80 speedily carry off the heat.

The invention may be carried out in several ways. The burner tube may be threaded externally and the burner tip internally, so that the neck of the tip incloses the tube. This arrangement is known but does not in 85 itself suffice to prevent the formation of said layer and the rupture of the tip. One way of carrying out the invention now consists in filling up the space between the threads on the burner tube and the tip with a suitable lute or cement.

2. The end of the metallic burner tube may be made of a metal resisting the above mentioned damaging reaction.

3. The end of the metallic burner tube 95 may be covered with a coating resisting the above mentioned injurious chemical reaction, and which may be either a metal or a suitable non-metallic material. Such a coating may be inseparably fastened to the metal 100 underneath it by soldering or by electrolytic deposition or some other process (e.g., Schoop's method) or may consist of a cap or ring which is screwed or pressed in or on the burner tube.

4. Any combination of the three methods

mentioned above may be applied so that for instance a lute or cement may be used simultaneously with a burner tube made of a chemically resistant metal, or covered with 5 a chemically resistant layer.

These means fully prevent the breaking off of the burner tip.

The following materials either alone or in mixture, may be used either as ingredients 10 for a suitable lute or cement or as a material of which the end of the burner tube may be made or with which it may be covered. Aluminium, chromium, gold, silver, nickel, cobalt, tantalum, tungsten, molybdenum, the 15 metals of the platinum group; boracic acid, anhydrous boracic acid, borax and other fusible borates, anhydrous silicic acid, water-glass, fusible silicates, glass, enamel, asbestos, aluminium oxid, clay, China clay, chamo- 20 motte, magnesia and other metallic oxids.

To the expert it may of course be left to make the best choice in every particular case. Only some examples are stated here with which especially good results have 25 been obtained.

For the first method of execution (a lute between the burner tube and the tip) a lute may be employed which consists of powdered asbestos, aluminium powder and wa- 30 terglass in suitable proportions; lutes in which clay, China clay, magnesia, chamoite or the like form part of the composition also suit the purpose very well.

As a metal out of which the end of the 35 burner tube may be formed or with which it may be covered nickel either pure or alloyed is especially suitable, because it is not too expensive. A thin film of silver however also suits the purpose and is not too expensive 40 either. Certain alloys may of course be used as well.

A very suitable material for protecting the end of the burner tube is also enamel or molten silica.

45 Though borax when used in a lute will melt, it is still very suitable if it is mixed with asbestos fibers or the like on account of its property to absorb metallic oxids.

Embodiments of the invention are shown 50 in Figures 1-6 of the drawings;

Fig. 1 shows a metallic burner tube B,

carrying a tip A, the space between the threads being filled up by a lute L;

Fig. 2 is similar to Fig. 1 but shows a different arrangement of the threads;

Fig. 3 shows a burner tube B the end of which is made of a chemically resistant metal R;

Fig. 4 shows the tube B with a cover of chemically resistant metallic or non-metallic 60 material M;

Fig. 5 is similar to 3 and illustrates the use of a lute L; in addition to making the end of the burner tube of a chemically re- 65 sistant metal R;

Fig. 6 is similar to Fig. 4 and illustrates the use of a lute L, in addition to covering the end of the burner tube with a chemically 70 resistant metal M.

It will, of course, be understood that various 70 modifications may be effected in the described invention without departing from the scope and spirit thereof.

Having thus described my invention, what I claim as new and desire to secure by Let- 75 ters Patent is:—

1. In an inverted burner, a burner tube, a tip and a layer of a material on the portion of said burner tube engaging with said tip which will effectively resist the chemical 80 action of the gases of combustion upon the burner tube.

2. In an inverted burner, a burner tube, a tip and a layer of a metallic material on the portion of said burner tube engaging with 85 said tip which will effectively resist the chemical action of the gases of combustion upon the burner tube.

3. In an inverted burner, a burner tube, a tip and a layer of nickel on the outer surface 90 of the portion of said burner tube engaging with said tip, said layer of nickel serving to effectively protect said burner tube from the chemical action of the gases of combustion thereon.

In testimony whereof I affix my signature in presence of two witnesses.

JOHAN KAREL FREDERIK BLOKHUIS.
